TEARING GUIDE FOR RATION BOOK
STAMPS

Henry D. Noel, New York, N. Y.

Application April 10, 1943, Serial No. 482,653

4 Claims. (Cl. 283—12)

This invention relates to tearing guides for use in the tearing of stamps or coupons from books.

The primary object of the invention resides in a tearing guide for use in facilitating the neat and easy tearing of stamps or coupons from ration books.

Another feature of the invention is to provide a tearing guide which is captively carried by the book for ready sliding to aligned position with the stamp to be torn away for use.

A further feature of the invention is the provision of a tearing guide which is formed from a single piece of flat rigid material such as Celluloid, plastic, fibre, or the like; which is inexpensive of manufacture; and which may contain an advertisement and the guide to be given away by the advertiser.

Other novel features of the invention will become apparent as the following specification is read in conjunction with the accompanying drawing, in which,

Figure 1 is a perspective view of the tearing guide per se.

Figure 2 is a top plan view of a ration book in open position with the tearing guide overlying one of the inside pages for use.

Figure 3 is a vertical sectional view on the line 3—3 of Figure 2, the dotted lines indicating the guide swung over the opposite page for use thereon.

Referring to the drawing by reference characters, the numeral 10 designates my tearing guide device in its entirety which is constructed of a single piece of relatively thin flat stiff material such as, Celluloid, fibre, plastic or the like. For reasons to be hereinafter explained, I prefer to make the device 10 of a transparent Celluloid or plastic substance, but the same may be made of a non-transparent substance if desired.

The tearing device 10 includes a leaf-like body 11 having a straight vertical side edge 12. Adjacent the side edge 12, the body 11 is provided with a vertical elongated rectangular shaped slot 13, the same being of a length equal to or slightly greater than the height of the book to which the tearing guard device is to be operatively connected. Thus the maximum height of the body 11 is slightly greater than the height of the book to which it is to be connected. The side edge of the body 11 opposite to the edge 12 is provided with a series of upwardly receding step portions 14, three of which are shown in the drawing, although more or less may be provided, depending upon the number of horizontal

rows of stamps or coupons arranged within the pages of the book. Each step portion 14 comprises a straight horizontal tearing guide edge 15, equal in length to the width of the stamp or coupon to be torn away, and a straight vertical tearing guide edge 16 of a length equal to the height of the stamp or coupon to be torn away. The tearing guide edges 15 and 16 of each step portion are disposed at right angles to each other and cooperate to provide a continuous angular tearing guide edge for any one stamp or coupon of a horizontal row bound in a book. Extending at right angle to the lowermost horizontal tearing guide edge 15 is a vertical tearing guide edge 16a, which functions to facilitate the tearing away of the stamps or coupons of the bottom horizontal row.

In order that the stepped tearing guide portions of the body 11 will lie within the confines of the pages of a book, the lower edge of the same is stepped inwardly as at 17.

In Figures 2 and 3 of the drawing, I have illustrated the tearing guide device 10 as being applied for use upon a Government food ration book 18 which includes flexible front and back covers 19—19 within which pages 20 are bound. The pages 20 are provided with vertical and horizontal lines of tear 21 and 22 respectively which may or may not be perforated and which in this instance divides each page into four horizontal and six vertical rows of stamps or coupons 23, suitably printed with indicia indicating their "point" value and an identifying symbol for period of use.

In use, the tearing guide device 10 is operatively associated with the ration book 18, by first opening the book to the page containing the stamps or coupons for current use. One end of the open book is threaded through the slot 13 with the stepped tearing guide edge overlying the open pages of the book as best illustrated in Figure 2. Normally, the device 10 is slid to a position so that the slot 12 is in alignment with the hinge connection 24 between the pages 20 and covers 19—19 to enable the closing of the book with the stepped tearing guide portion sandwiched between adjacent pages. Due to the fact that the ends of the slot 12 terminates adjacent the top and bottom edges of the body 11, the narrow width of the material therebetween is capable of flexing to enable the flat positioning of the body 11 over the pages of the book. However, when the book 18 is opened, the device 10 is free to be swung to a position over either the right or left page and subsequently slid to a position

in alinement with the boundary edges of the selected stamp or stamps 23 to be torn free. For instance, if stamp "H8" is to be torn free, the device 10 is slid over to a position to cause the tearing guide tearing edges 15 and 16 to aline with the tear lines 21 and 22 which form right angle side boundaries of said stamp, whereas the free corner of the stamp is grasped and torn by pulling the same against the guide tearing edges 15 and 16. Should it be desired to tear away any of the "1" volume stamps, the edge 16a is brought into alinement with the tear line 21 forming one side boundary of said stamp. Other stamps along intermediate rows may be removed by operations similar to that described for the tearing away of stamp "H8". Assuming that stamps on the opposite page are to be torn free, the device 10 may be swung to a position thereover as shown in dotted lines in Fig. 3. The transparency of the device 10 permits the viewing of underlying stamps and enables the more rapid positioning of the device with the selected stamps to be torn away.

By the use of the tearing guide device 10 upon ration books, it is possible for a purchaser to expedite the removal of the stamps in the presence of the store clerk, and enables the stamp to be torn evenly. Furthermore, it prevents accidental mutilation of the stamps and imparts a neat appearance to the partially used pages of the book. Also, the device 10 acts as a marker to enable the holder of the book to quickly turn the pages bearing current use stamps.

The tearing guide device 10 is relatively simple and inexpensive of manufacture and may be used by the manufacturers of food products in good-will advertising by placing an advertisement upon either or both sides of the body 11.

While I have shown and described what I consider to be the preferred embodiment of my invention, I wish it to be understood that such changes in construction, design, and material may be resorted to if desired without departing from the spirit of the invention as set forth in the appended claims.

Having thus described the invention, what I claim as new and desire to secure by Letters Patent of the United States, is:

1. A tearing guide comprising a relatively thin flat stiff body having a vertical elongated slot adjacent one of its side edges to threadedly receive the open pages of a coupon book, the other side edge of the body having a series of stepped tearing edges adapted to be brought into selective alinement with two sides of the boundaries of the coupons to be torn from the pages.

2. A tearing guide comprising a leaf-like body of thin stiff transparent material having a straight vertical slot adjacent one of its side edges for threadedly receiving the open pages of a multiple coupon page book, the other side edge of the body having a series of upwardly receding right angle step tear guide edges adapted to be brought into selective registration with the two sides of the tear boundaries of the coupons to be torn free from the pages.

3. In combination, a book having bound pages of vertical and horizontal crossing rows of tear away stamps, a tearing guide device comprising a leaf-like body of stiff material having a vertical elongated slot, said book having pages threaded through said slot whereby the guide is slidably and hingedly connected to said book with a portion disposed therein between adjacent pages, that portion disposed within the book having a stepped tearing edge for selective alinement with the stamps to be torn from the pages when the book is opened thereto.

4. In combination, a book having bound pages of vertical and horizontal crossing rows of tear away stamps, a tearing guide device comprising a leaf-like body of stiff material, means on said body for slidably mounting the same upon the book to lie between adjacent pages thereof, and upwardly receding stepped tearing edges provided on said body for selective registration with two of the boundaries of a tear away stamp to guide the tearing away thereof from the bound pages.
